(57) **CLAIM**

The ornamental design for an self condensing dental amalgam carrier with single step loading performance, substantially as shown and described.

DESCRIPTION

FIG. 1 is a top, left-side perspective view of the self condensing dental amalgam carrier with single step loading performance.

FIG. 2 is a bottom, left-side perspective view thereof;

FIG. 3 is a front elevation view thereof;

FIG. 4 is a rear thereof;

FIG. 5 is a left side elevation view thereof;

FIG. 6 is a right side elevation view thereof;

FIG. 7 is a bottom plan view thereof;

FIG. 8 is a top plan view thereof;

FIG. 9 is a cross-section thereof along the plane of lines 9-9 of FIG. 5.

FIG. 10 is a cross-section thereof along the plane of lines 10-10 of FIG. 5. For clarity of illustration, so that the details of the design will be easier to see, a portion of the design is enlarged.

FIG. 11 is a cross-section thereof along the plane of lines 11-11 of FIG. 7.

FIG. 12 is a cross-section thereof along the plane of lines 12-12 of FIG. 7. For clarity of illustration, so that the details of the design will be easier to see, portions of the design are enlarged.

FIG. 13 is a top, left-side perspective view of the inner member of the dental amalgam carrier. The cover has been removed from the end of the inner member in the enlarged area; and,

FIG. 14 is a left-side view of the inner member of the dental amalgam carrier. The cover has been removed from the end of the inner member in the enlarged area.
